CLAIM

The ornamental design for a gliding tiered expanded mesh shelf, as shown and described.

DESCRIPTION

FIG. 1 is a top perspective view of a first embodiment of a gliding tiered expanded mesh shelf shown with environment;

FIG. 2 is an elevational view of a first end of the gliding tiered expanded mesh shelf of FIG. 1;

FIG. 3 is an elevational view of a second end of the gliding tiered expanded mesh shelf of FIG. 1;

FIG. 4 is a top plan view of the gliding tiered expanded mesh shelf of FIG. 1;

FIG. 5 is a bottom plan view of the gliding tiered expanded mesh shelf of FIG. 1;

FIG. 6 is an elevational view of a first side of the gliding tiered expanded mesh shelf of FIG. 1;

FIG. 7 is an elevational view of a second side of the gliding tiered expanded mesh shelf of FIG. 1;

FIG. 8 is a top perspective view of a second embodiment of a gliding tiered expanded mesh shelf shown with environment;

FIG. 9 is an elevational view of a first end of the gliding tiered expanded mesh shelf of FIG. 8;

FIG. 10 is an elevational view of a second end of the gliding tiered expanded mesh shelf of FIG. 8;

FIG. 11 is a top plan view of the gliding tiered expanded mesh shelf of FIG. 8;

FIG. 12 is a bottom plan view of the gliding tiered expanded mesh shelf of FIG. 8;

FIG. 13 is an elevational view of a first side of the gliding tiered expanded mesh shelf of FIG. 8;

FIG. 14 is an elevational view of a second side of the gliding tiered expanded mesh shelf of FIG. 8;

FIG. 15 is a top perspective view of a third embodiment of a gliding tiered expanded mesh shelf shown with environment;

FIG. 16 is an elevational view of a first end of the gliding tiered expanded mesh shelf of FIG. 15;

FIG. 17 is an elevational view of a second end of the gliding tiered expanded mesh shelf of FIG. 15;

FIG. 18 is a top plan view of the gliding tiered expanded mesh shelf of FIG. 15;

FIG. 19 is a bottom plan view of the gliding tiered expanded mesh shelf of FIG. 15;

FIG. 20 is an elevational view of a first side of the gliding tiered expanded mesh shelf of FIG. 15;

FIG. 21 is an elevational view of a second side of the gliding tiered expanded mesh shelf of FIG. 15;

(Continued)

FIG. 22 is a top perspective view of a fourth embodiment of a gliding tiered expanded mesh shelf shown with environment;

FIG. 23 is an elevational view of a first end of the gliding tiered expanded mesh shelf of FIG. 22;

FIG. 24 is an elevational view of a second end of the gliding tiered expanded mesh shelf of FIG. 22;

FIG. 25 is a top plan view of the gliding tiered expanded mesh shelf of FIG. 22;

FIG. 26 is a bottom plan view of the gliding tiered expanded mesh shelf of FIG. 22;

FIG. 27 is an elevational view of a first side of the gliding tiered expanded mesh shelf of FIG. 22; and,

FIG. 28 is an elevational view of a second side of the gliding tiered expanded mesh shelf of FIG. 22.

The broken lines showing is included for the purpose of illustrating environment and forms no part of the claimed design.

The break lines shown in FIGS. 1, 8, 15, and 22 are not part of the claimed design and represent that no particular length is claimed.
